DESULFURIZATION OF PETROLEUM HYDROCARBONS WITH AQUEOUS CAUSTIC SODA AND FORMALDEHYDE

Charles W. Rippie, Ashland, Ky., assignor to Ashland Oil & Refining Company, Ashland, Ky., a corporation of Kentucky

Filed Mar. 18, 1958, Ser. No. 722,212

6 Claims. (Cl. 208—231)

This invention relates to the purification of petroleum hydrocarbons and is directed particularly to the desulfurization thereof.

A principal objective of this invention has been to provide a process by means of which sulfur compounds present in liquid hydrocarbons such as gasoline may be removed in an easy and inexpensive way.

A further objective of the invention has been to provide a process for improving the lead susceptibility and stability of hydrocarbon motor fuels such that a given octane number may be achieved by the incorporation of a relatively smaller amount of tetraethyl lead and such that the amount of inhibitors conventionally added may be reduced.

The adverse affect of small quantities of sulfur compounds contained in a hydrocarbon motor fuel upon the lead susceptibility thereof is well understood, and various processes are now used to reduce such sulfur content to a minimum consistent with the cost of treatment and the savings in lead cost to be obtained thereby. However, it is generally impractical or impossible for the refiner to endeavor to obtain complete desulfurization because the processing cost would exceed the savings that would be derived from the improvement in lead susceptibility. While the sulfur content of liquid hydrocarbon motor fuels varies according to the method by which they are obtained, it is not unusual for catalytically cracked gasoline or motor fuel fractions to contain from 0.02 to 0.10% sulfur depending upon feed stock, catalyst, severity of processing, and other conditions and for straight-run gasolines to contain still more.

It has long been known that treatment of a liquid petroleum hydrocarbon containing organic sulfur with caustic soda in aqueous solution is capable of converting some of the sulfur compounds into substances which are more soluble in the caustic solution than in the hydrocarbon and which therefore are removed from the hydrocarbon upon separation of the aqueous alkali therefrom. The reaction and dissolution are rapid, and the cost of treatment is reasonable inasmuch as the caustic soda solution, after use, may be regenerated for reuse. However, caustic soda treatment is effective in removing only those sulfur compounds which are of the RSH type, e.g., mercaptans. Organic sulfides of the R₂S type remain substantially unaffected, yet they constitute a substantial percentage of the total sulfur content and impair the lead susceptibility of the fuel in which they are present.

An objective of the present invention has been to provide a desulfurizing process of the caustic soda type but modified to effect removal of organic sulfides of the R₂S type simultaneously with removal of sulfur compounds of the RSH type contained in the petroleum hydrocarbon. More specifically, an objective of the invention has been to provide a desulfurizing process of the caustic soda type wherein the total sulfur content may be reduced to a greater degree than with the use of caustic soda alone.

Briefly, this invention is directed to a process of desulfurization wherein liquid petroleum hydrocarbon con-

2

taining sulfur compounds, but which is free or substantially free of hydrogen sulfide, is contacted conjointly with a strong aqueous solution of caustic soda and a small amount of formaldehyde, whereby the total sulfur is reduced materially and the lead susceptibility of the product is substantially improved in comparison with the lead susceptibility of the same hydrocarbon feed stock treated with caustic soda only.

Although the use of formaldehyde previously has been proposed as a desulfurizing agent in processes wherein strong acid, high temperature, or molten sodium has been employed, it has now been found that a substantial reduction of total sulfur readily can be achieved in a much simpler way and at low or ordinary processing temperature by contacting the organic sulfur-bearing hydrocarbon simultaneously with caustic soda and a small quantity of formaldehyde, for instance 1 part formaldehyde to 15,000 to 40,000 parts by volume of hydrocarbon being treated. In fact, an important feature of the present invention resides in the use of an amount of formaldehyde which, even when in commercial aqueous solution is so small that it does not dilute the caustic soda solution by a significant amount or adversely affect the regenerability thereof.

Peculiarly, treatment of hydrocarbon feed stock with caustic soda and formaldehyde simultaneously or conjointly provides a greater reduction of total sulfur content than that obtained by contacting the feed stock successively with caustic soda only, then formaldehyde without caustic soda, or vice versa. The chemical mechanism by which such results are obtained is not fully understood; it is possibly that the caustic soda, while converting mercaptans into mercaptides in the usual manner, promotes reaction of the formaldehyde with compounds of the R₂S type with which formaldehyde alone does not possess the ability to react. In any event, the addition of an apparently negligible quantity of formaldehyde in the presence of caustic soda has been found consistently to decrease the total sulfur content by an amount which is 20-40% greater than is furnished by caustic soda alone, and permits 0.5 to 0.6 cc. per gallon less tetraethyl lead to be added to the motor fuel than is otherwise required to produce a given octane number in the same stock desulfurized by caustic soda only.

Formaldehyde and caustic soda in aqueous admixture react with one another at ordinary temperatures to produce sodium formate and alcohol, neither of which possesses desulfurizing properties. Therefore, in the practice of the present invention it is desirable to introduce the formaldehyde into contact with the caustic soda and hydrocarbon in such manner that desulfurization of the hydrocarbon by the conjoint action of the caustic soda and formaldehyde is accomplished before the formaldehyde is destroyed through reaction with the caustic soda. This may be accomplished conveniently by introducing the formaldehyde into the caustic soda solution at a point just ahead of that at which contact with the hydrocarbon is established, or by introducing the formaldehyde at the site wherein the caustic soda is brought into contact with the hydrocarbon. In either manner the formaldehyde is caused to react with organic sulfur components before undesirable pre-desulfurizing reaction occurs between the formaldehyde and the caustic soda. In general, however, the process of this invention, except as to addition of formaldehyde, may be the same as a conventional caustic soda desulfurization process as practiced in the various ways known to the art.

The invention is further predicated upon the discovery and determination that a spent caustic soda solution in which formaldehyde has been incorporated to promote greater desulfurization of hydrocarbon in the treatment

is more easily regenerated than when no formaldehyde has been incorporated. For example, in a conventional caustic soda regeneration process wherein the sulfide content of the spent solution is converted into removable disulfides by blowing with air, the spent solution must be held at appreciable temperature and must be blown for an appreciable period of time in order to provide a suitable degree of regeneration. In contrast with these requirements, the sulfides contained in spent caustic soda as produced in the desulfurization process of the present invention are converted into removable sulfur compounds in a rapid and efficient manner without increase in temperature, for example, merely by incorporating air into the spent caustic solution through use of an eductor or the like. The spent caustic solution produced in a desulfurizing process conducted according to the present invention readily may be regenerated by other known regeneration procedures.

One typical process of desulfurization followed by regeneration of the spent caustic solution is illustrated in the accompanying drawing. Sulfur-containing gasoline (or other hydrocarbon to be desulfurized) but from which hydrogen sulfide has been removed by any suitable means enters the system through line 1 wherein it mixes with caustic soda solution from the line 2. Aqueous formaldehyde solution is admitted to the stream through line 3. The caustic soda solution provided in line 2 may be fresh aqueous caustic soda solution or may be a solution which has been regenerated in various ways, one of which is subsequently described.

In typical caustic soda desulfurization, the aqueous caustic solution used may contain approximately 10% by weight of caustic soda (or caustic potash) in water, and the flow rate is adjusted to provide approximately one part by volume of caustic soda solution to five parts by volume of gasoline, but it is understood that substantial variations in the caustic-gasoline ratio may be made to suit the requirements of given feed stocks.

In the preferred practice of the invention, the formaldehyde employed is a commercial 37% aqueous formaldehyde solution known in the trade as formalin. This solution may be metered into the caustic soda stream solution of line 2 at a rate of one part by volume of formalin to about 15,000-18,000 parts by volume of sour gasoline charged into the system through line 1. However, in place of using formaldehyde as a 37% aqueous solution, which was chosen because of its commercial availability and cheapness, other concentrations may be used. In general, no economic benefit has been found in using formaldehyde in greater proportion to the gasoline or caustic soda than that indicated. In the system shown, the formaldehyde flow rate is controlled by means of a proportioner 4 or suitable pump and metering valve. As subsequently explained, the pressure in line 2 may be approximately 200 p.s.i.

The stream containing sour gasoline, caustic soda solution, and formaldehyde flowing in line 5 passes through a differential pressure control valve indicated generally at 6, beyond which the stream passes into a knock-out or settling drum 7. At the pressure control valve 6 the pressure on the stream is reduced to approximately 25 p.s.i., and the valve functions as a mixing valve bringing the components of the stream into intimate contact with one another. It will be seen that the point at which formaldehyde is introduced into the system is relatively closely adjacent the point at which sour gasoline is introduced into the system, whereby the formaldehyde and caustic soda contact the gasoline before any significant reaction occurs between the caustic soda and the formaldehyde. If desired, however, the formaldehyde may be introduced directly into line 1 or all three components may be commingled at a single point e.g. the mixing valve 6.

At the knock-out drum 7, aqueous caustic soda settles from the gasoline which, as a now desulfurized prod-

uct, passes through line 8 to storage. Desulfurization of the gasoline occurs in the period of transit of the stream to the knock-out drum and during the time of residence therein while separation of the caustic soda solution from the gasoline occurs. Spent aqueous caustic soda is removed from the bottom layer in the knock-out drum through line 9 which connects to receiver 10.

For regeneration of the spent caustic solution, a pump 12 having its intake line connected to tank 10, discharges through line 13 to a tank 14. However, to facilitate introduction of air into the stream, the pump 12 operates in conjunction with a recirculation system 15 to which air is introduced in quantity sufficient to cause conversion of organic sulfides in the spent caustic soda solution into disulfides which may be removed by washing as later described. As shown, the recirculation system comprises a line 16 connected to the pump discharge line 13 and a line 17 which is connected to the line 16 and which leads to the intake side of pump 12. Line 16 is valved as at 18 to cause a predetermined portion of the pump effluent to recirculate through the line 17, and air may be introduced into the recirculating stream by means of a conventional eductor 19 before the stream is returned to the system. In place of the eductor, air may be introduced into the caustic soda stream in any other suitable manner. The significant point is that conversion of sulfides to disulfides in the spent caustic soda solution is very rapid. Some of the caustic soda solution from pump 12 bypasses the eductor system, but the air absorbed into the recirculated stream is adequate to effect conversion to disulfides of the entire spent caustic soda solution through the commingling which occurs in the pipes, pump and tank 14.

A pump 20 delivers the air-treated caustic soda solution from tank 14 through a line 21 to a disulfide scrubber 22 wherein the solution is washed with a solvent, such as the conventionally used naphtha, capable of dissolving the disulfides therefrom.

In the scrubber system shown, a column of naphtha is maintained within tank 22 above a lower layer of caustic soda solution. To facilitate washing, the naphtha phase is recirculated into contact with the caustic soda stream flowing through pipe 21; for this purpose the recirculating system includes an outlet line 23 which is located above the caustic-naphtha interface and which leads to a pump 24. The pump discharges through a line 25, into line 21, and both streams pass through a mixer 26, then into the upper part of the disulfide scrubber 22. The mixer 26 may be in the form of a box having an orifice plate therein to provide turbulence through which mixing is accomplished.

Within tank 22 the disulfide content of the caustic soda solution is sequestered in the naphtha, and regenerated caustic soda solution accumulates at the bottom of the tank from which it is withdrawn through a pipe 27 which connects to the caustic line 2 for reuse. Fresh caustic soda solution, as needed for charging or for make-up may be admitted to the system through line 28.

The naphtha phase containing disulfides may also be treated for reuse. In the system disclosed, naphtha is withdrawn from the upper part of the disulfide scrubber 22 through a line 30 which leads to a knock-out drum 31, wherein entrained caustic soda solution is allowed to settle from the naphtha as a lower layer which may be withdrawn as necessary. The solvent is discharged from the knock-out drum through a line 32 leading to a flash tower 33 which may be suitably packed. To facilitate vaporization of naphtha, the lower portion of the flash tower 33 may be maintained at a temperature of approximately 275° F. by recirculation of naphtha through a steam reboiler 34 which is supplied from line 35 and which returns heated liquid to the flash tower through line 36. By vaporization, the upper portion of the flash tower is maintained at a suitably lower temperature, for example,

200° F. whereby desulfurized naphtha vapors are generated which leave the tower through line 37 and pass to a condenser 38.

Condensed naphtha is collected in an accumulator tank 39 from which a line 40 returns the desulfurized naphtha solution to the disulfide scrubber. In the system shown, the accumulator tank is provided with a liquid level controller indicated generally at 41 which controls the motor of a pump 42 installed in line 40 whereby the pump delivers naphtha from the accumulator to the disulfide scrubber in accordance with the rate at which it collects in the accumulator. Fresh naphtha may be charged into the system through the line 43.

It is also to be noted that the system for feeding naphtha to the reboiler 34 includes an outlet 44 which is valved as at 45. Since disulfides collect at the bottom of the flash tower, the higher heat of vaporization is employed as a means of maintaining the desired temperature differential in the flash tower. By the manipulation of valve 45, disulfides at the bottom of the flash tower readily may be discharged from the system.

In the practice of the process of this invention desulfurization of the hydrocarbon proceeds rapidly at or about room temperature, for example from 70 to 100° F. While the rate of oxidation of sulfur compounds contained in the spent caustic may be increased by increasing the solution temperature during regeneration, that procedure is not required when the spent caustic solution contains spent formaldehyde since the oxidation rate is sufficiently rapid for practical purposes without temperature increase. Also, while the system has been shown for use in desulfurizing straight-run or cracked gasolines, it is to be understood that the latter term is intended to include motor fuels produced by alkylation, reforming, isomerization, or other methods. It is also to be understood that the desulfurizing advantages afforded by the use of formaldehyde with caustic soda may be utilized in nonregenerative methods of caustic treatment where the organic sulfur content is sufficiently low to permit wasting of the spent treating solution. Similarly, the invention is adapted to be used for removing sulfur from hydrocarbons heavier than fractions burning in the gasoline range, such as fuel oils, in which organic sulfides seriously interfere with utilization.

In typical operation of the process for desulfurizing gasoline, the average research octane number of the treated i.e. desulfurized gasoline with 3 cc. of tetraethyl lead added per gallon and adjusted to 8# RVP, was 84.35 when caustic soda only was used for desulfurization, while an octane number of 85.80 (based on the same TEL addition) was obtained when caustic soda and formaldehyde were used for desulfurization of the same hydrocarbon—an increase of 1.45 octane. Thus, the conjoint use of formaldehyde and caustic permits a saving of 0.6–0.7 cc. or more of tetraethyl lead per gallon of gasoline. In terms of cost at the current price of tetraethyl lead, the amount thereof required to produce the given octane number was \$56.55 per thousand barrels, while the cost of formaldehyde required for the treatment of 1000 barrels was \$2.75. The cost of regeneration is the same in either case.

The following table shows the comparison of total sulfur content of gasolines desulfurized with caustic soda and with caustic soda and formaldehyde in accordance with the present invention:

	Percent S Without CH ₂ O	Percent S With CH ₂ O	TEL/gal. Savings
1. Dubbs-----	0.0243	0.0126	0.5
2. Regular-----	0.0408	0.0280	0.5
3. Regular-----	0.0308	0.0243	0.6
4. Ethyl-----	0.0217	0.0123	0.8
5. Ethyl-----	0.0217	0.0150	0.7
6. Ethyl-----	0.0336	0.0152	0.5

Extensive tests have shown further that on an average treatment with caustic soda and formaldehyde reduces RSH sulfur by 35.5%, R₂S sulfur by 23.8%, and total sulfur by 23.4%, and less inhibitor, therefore, is required to meet specifications for gums of the treated gasoline.

Tests of gasoline desulfurized according to the invention also show that stability, as measured on copper and glass dishes, is improved, and less inhibitor therefore is required to meet specifications for gums of the treated gasoline.

In place of using naphtha to wash disulfides from the caustic soda solution, other suitable solvents may be used as readily will be understood by those skilled in the art. Similarly, as previously explained, it is to be understood that the recirculation system herein disclosed is merely typical and that other systems for recirculating spent caustic solution readily may be used. Thus, the introduction of formaldehyde into the caustic soda treating solution not only increases the degree of desulfurization over that which could be obtained by the use of caustic soda only, but renders the spent caustic soda solution more amenable to regeneration.

Having described my invention, I claim:

1. The process of desulfurizing liquid petroleum hydrocarbon containing alkyl sulfide type sulfur compounds which method comprises, contacting the petroleum hydrocarbon with aqueous caustic soda solution and introducing into contact with both components, while excluding oxygen, a quantity of formaldehyde in the proportion of 1 part thereof to each 15,000–18,000 parts of said hydrocarbon thereby to effect conjoint reaction of the caustic soda and formaldehyde with alkyl sulfide type sulfur compounds present in the hydrocarbon, then separating from the petroleum hydrocarbon the said aqueous caustic soda solution and sulfur compounds dissolved therein derived from said alkyl sulfides, and regenerating the separated caustic soda solution for reuse by contacting the same with air.
2. A method of treating a petroleum hydrocarbon to reduce the amount of alkyl sulfide type sulfur compound impurities therein which method comprises, bringing streams of aqueous caustic soda solution and the said petroleum hydrocarbon into liquid contact with one another and, which excluding oxygen, introducing formaldehyde into the stream of aqueous caustic soda solution at a point just ahead of the point of liquid contact thereof with the hydrocarbon stream in the amount of approximately one part of formaldehyde to 15,000–18,000 parts by volume of the said hydrocarbon whereby the formaldehyde reacts with sulfur compounds in the said hydrocarbon before substantial reaction thereof with the caustic soda occurs.
3. A method of treating a petroleum hydrocarbon containing R₂S and RSH type sulfur compounds to reduce the amounts thereof which method comprises, continuously, while excluding oxygen, bringing streams of aqueous caustic soda solution and the said petroleum hydrocarbon into liquid contact with one another and with a small quantity of formaldehyde in the amount of approximately one part of formaldehyde to 15,000–40,000 parts by volume of petroleum hydrocarbon whereby the formaldehyde and caustic soda act conjointly to remove R₂S and RSH type sulfur compounds from the hydrocarbon.
4. The method of claim 3 wherein the treatment is conducted at approximately room temperature.
5. The method of claim 3 wherein the treatment is conducted at approximately room temperature and wherein spent caustic soda solution produced in the treatment is subsequently regenerated for reuse by introduction of air therein.
6. The method of removing objectionable alkyl sulfide compounds from hydrocarbon motor fuel which method

comprises, treating said motor fuel, while excluding oxygen, with a desulfurizing reagent consisting of aqueous caustic soda solution and aqueous formaldehyde solution in which reagent the formaldehyde constitutes approximately 1 part by weight per 15,000 to 40,000 parts of hydrocarbon being treated, then regenerating the caustic

8
soda solution for reuse by introducing air therein, then separating the reagent from the hydrocarbon motor fuel.
